UNITED STATES PATENT OFFICE

NATHANIEL C. GREENE, OF NEW YORK, N. Y., ASSIGNOR TO POLYMET MANUFACTURING CORPORATION, A CORPORATION OF NEW YORK

ELECTRICAL PLUG

Application filed May 19, 1926. Serial No. 110,080.

This invention relates generally to electrical plugs of the telephone type adapted for use in connection with radio receiving sets or telephones to improve the quality of the tone reproduction at the loud speaker or head phones; the plug being so constructed to receive a plug terminal or metal tips connected to the ends of the lead wires from said loud speaker or head phones.

10. The improved quality of the tone reproduction is obtained by inserting a condenser across the terminals of the plug. This condenser improves both the high and low notes of the musical register by broadly increasing the audio frequency range. The condenser also by-passes the stray radio frequency currents which pass over into the audio stages of the set and also prevents the pulsating current obtained from faulty "B" batteries from passing through the speaker unit; thereby eliminating the crackling and other foreign noises due to these stray currents which are greatly amplified by the loud speaker and cause poor reproduction.

25. By inserting the condenser in the body portion of the plug, I accomplish the results immediately which would otherwise require considerable changes to be made in a large percentage of the radio sets in use to-day as they are so enclosed and constructed to practically necessitate taking the set apart to insert the condenser in the hook-up; and if the set were accessible, the average layman would not know where the condenser was to be attached nor would he know how to attach it.

30. My improved phone plug also provides for the possibility of operating a plurality of loud speakers or sets of head phones. This provision is made by providing the body portion of the plug with binding posts which are in contact with the condenser connections.

One of the objects of my invention is to 45 provide a radio phone plug which will improve the quality of the tone reproduction.

Another object of my invention is to increase the audio frequency range of a radio receiving set and thereby improve the high 50 and low notes of the musical register,

Another object of my invention is to eliminate the stray radio frequency currents and prevent the pulsating current from faulty "B" batteries from passing through the speaker unit.

55. Another object of my invention is to provide a radio phone plug with means for attaching more than one loud speaker or sets of head phones.

Another object of my invention is to provide a radio phone plug having a condenser located within its body portion and connected across its terminals which will improve the reproduction at the loud speaker or head phones, and which will eliminate the necessity of taking the receiving set apart or dismantling it to any extent to obtain the improved reproduction.

60. Another object of my invention is to provide a radio plug which will improve the reproduction and which is adapted to receive a plug terminal connection connected to the lead wires of a loud speaker or head phone.

65. Another object of my invention is to provide a neat, simple and inexpensive device 75 which will be attractive in appearance, durable and not subject to excessive strain or wear, and which entirely encloses a condenser and phone jack in a body portion of insulating material.

80. With these and other objects in view, to be more fully set forth hereinafter, the invention consists in the novel construction, combination of elements and arrangement of parts which will be exemplified in the operation and construction herein described in 85 the following specification and illustrated in the accompanying drawings.

89. The invention will first be described in connection with the accompanying drawings, 90 wherein similar reference characters are used to designate corresponding parts throughout the several views, and more specifically defined and indicated in the appended claims.

95. Attention is directed to the drawings in which:

Fig. 1 is a plan view of my improved radio plug,

Fig. 2 is a side view of same.

Fig. 3 is a plan view of the lower half illustrating the relative position of the parts,

Fig. 4 is a sectional view taken on the line 4-4 of Fig. 1,

Fig. 5 is a sectional view the same as Fig. 4 illustrating two types of loud speaker or head phone connections,

Fig. 6 is a sectional view taken on the line 6-6 of Fig. 1,

Fig. 7 is an end view looking in the direction of the arrows 7-7, Fig. 1, and

Fig. 8 is a central sectional view of a modified form of my invention.

Referring to the drawings, the body portion of my improved plug consists of the two halves 1 and 2, each of which are an exact replica of the other and preferably molded from a suitable insulating material such as hard rubber, bakelite, redmanol, porcelain or any other of the common insulating materials which can be molded. Each of the halves of the body portion have the recesses or depressions 3 molded in them to form the chamber 3^a when assembled and securely held in position by the countersink screws 4. (See Fig. 1.)

Located in suitable depressions in one end of the halves forming the body portion is the plug terminal assembly consisting of the terminals 5 and 6 which are insulated from one another by the washers 7 and 8. Securely held at one end of the terminal assembly and in electrical contact with the terminals 5 and 6 but insulated from each other by the washer 8, is the spring contact 9 and the terminal connector 10 respectively, to both of which is securely fastened the condenser 11 by means of the bolts 12.

The binding posts 13 and 14 are centrally located in suitable holes molded or drilled in the two halves 1 and 2 forming the body portion which are securely held in position by the threaded washers 15. The holes 16 drilled in said binding posts 13 and 14 provided for the reception of a second pair of lead wires for a loud speaker or head phones, (see Fig. 5), said wires being provided with metal tips 17 which are held in position by screwing down on the knurled thumb nuts 18. Lead wires from a second loud speaker or head phones not having metal tips are held in the usual manner of binding the bared ends around the binding post and then screwing down the thumb nut. The contact button of the binding post 13 is in contact with the contact spring 19 which is held in position by one of the bolts 12. To increase the strength of the spring contact 9 and to insure perfect contact between the binding post and the contact spring 19, said contact spring 19 is of such length to form a sliding contact near the end of the spring contact 9 to allow for deflection when the loud speaker or phone plug 20 is pushed home as illustrated in Fig. 5. The connector 10 is so

formed to be in electrical contact with the binding post 14. The angle piece 21 carries the contact collar 22 which is centered by suitable depressions in the halves 1 and 2. With the arrangement of parts as illustrated it will be readily seen that an electrical current coming in through the plug terminal 5 will pass through the spring contact 9 and into the plug terminal 5^a of the plug 20 which is a similar terminal and the current returning will pass from the terminal 6^a through the contact collar 22, the angle piece 21, the connector 10 and into the terminal 6; the condenser 11 acting as a by-pass for stray radio frequency currents and also prevents pulsating current from faulty "B" batteries from passing through the loud speaker or head phones.

Referring to the modified form as illustrated in Fig. 8 it will be seen that the binding posts 13 and 14 have been eliminated, thereby making it a single connection plug. The elimination of the binding posts also eliminates the contact spring 19 and allows a more simplified form of connector 10 to be used; all of which tends to decrease the cost of production.

In accordance with the provisions of the patent statute, I have described my invention but I desire it understood that it is not confined to the particular form shown and described, the same being merely illustrative, and that the invention can be carried out in other ways without departing from the spirit of my invention, and therefore, I claim broadly the right to employ all equivalent instrumentalities coming within the scope of the appended claims, and by means of which, objects of my invention are attained and new results accomplished; as it is obvious that the particular embodiments herein shown and described are only some of many that can be employed to attain these objects and accomplish these results.

Having now described my invention what I claim and desire to secure by Letters Patent is:—

1. In a device of the character described, a hollow insulating casing, a collar embedded in the end wall of said casing and extending from the exterior to the interior thereof, a bracket secured to the interior end of said collar and supported thereby within said casing but spaced from the side walls thereof, and means at the opposite end of said bracket for supporting a radio condenser of the square block type within said casing but spaced from the walls thereof and from said collar.

2. In a device of the character described, a hollow insulating casing of flat, generally rectangular formation, a collar embedded in the end wall of said casing and extending from the exterior to the interior thereof, a bracket secured to the interior end of said collar and supported thereby within said casing, said

- bracket being of L-shape formation with one limb surrounding said collar and the other limb extending along a side wall of said casing, close to but spaced from said wall, and means carried by the extremity of said last mentioned limb for supporting a radio condenser of the square block type within said casing, but spaced from the side walls thereof and from said collar.
- 5 3. In a device of the character described, a hollow insulating casing of flat, generally rectangular formation, a cylindrical conducting collar embedded in and extending through an end wall of said casing, a jack plug embedded in and extending through the opposite end wall of said casing, a bracket of conducting material secured to the inner end of said collar and supported thereby within said casing, said bracket being of L-shape formation
- 10 with one limb surrounding said collar and the other limb extending along a side wall of said casing, close to but spaced from said wall, and an attachment device carried by said last mentioned limb, said attachment device being
- 15 adapted to engage the eyelet of a radio condenser of the square block type whereby said condenser is supported within but free of the walls of said casing and in electrical connection with said collar.
- 20 30. This specification signed this 17th day of May, 1926.

NATHANIEL C. GREENE.
